UNITED STATES PATENT OFFICE.

LOYD J. CALDWELL, OF BOURBON, INDIANA.

FEED-MILL.

SPECIFICATION forming part of Letters Patent No. 225,562, dated March 16, 1880.

Application filed September 27, 1879.

To all whom it may concern:

Be it known that I, LOYD JOSEPH CALDWELL, of Bourbon, in the county of Marshall and State of Indiana, have invented certain new and useful Improvements in Feed-Mills; and I do hereby declare that the following is a full, clear, and exact description of the invention, which will enable others skilled in the art to which it appertains to make and use the same, reference being had to the accompanying drawings, which form a part of this specification, and in which—

Figure 1 is a side elevation. Fig. 2 is a longitudinal vertical section. Fig. 3 is a transverse horizontal section through line xx , Fig. 1. Fig. 4 is a side view of the vertically-reciprocating grinding-plate detached from its casing, and Fig. 5 is a vertical section through line yy in Fig. 1.

Similar letters of reference indicate corresponding parts in all the figures.

This invention relates to feed mills or grinders of that class in which the grinding is performed by a vertically-reciprocating shaft working within a vertical casing, said shaft and casing being provided with grinding-plates the contiguous faces of which are roughened or serrated; and it consists in the improved construction and combination of operating parts, as hereinafter more fully described, and particularly pointed out in the claims.

In the drawings, A is the vertically-reciprocating pitman or pump-rod of a windmill, which is inserted into a central enlargement or square socket, a , in the grinder-plate B, and secured therein by a detachable bolt, b . Both faces of the reciprocating grinder-plate B are serrated in lines sloping toward the central longitudinal enlargement, a , at gradually-increasing pitch from top to bottom; but the corresponding serrations on opposite sides of the plate alternate with each other, those on one side being half a space ahead or behind their mates on the opposite side, so that when the plate is reciprocated they crush the grain alternately, and not simultaneously, on both sides of the plate, thus equalizing the strain upon the pump-rod or pitman.

The serrations $c' c'$ on both sides of the grinder-plate point with their edges in a downward direction, so as to break the whole grain

as it is being fed into the mill on the down-stroke, while the lower serrations, $c c c$, grind up the broken grain on its passage between the grinder-plate and contiguous serrated faces of 55 the casing.

The three longitudinal faces upon each side of the central socket or enlargement, a , are serrated, as shown at d , uniformly with the rest of their blade side.

C are the serrated casing-plates, which are arranged within a frame, D, provided with set-screws $f f'$ at the top and bottom, the inner ends of which bear against plates C C, so that by adjusting these screws the plates may be 65 set to grind fine or coarse, as desired.

The frame D is bolted upon suitably-arranged braces or supports in the mill-tower, and has a hopper, E, at its upper end, inside of which is arranged the vertical adjustable feed-gate F, 70 consisting of two parallel plates united at the top and ends by narrow plates G G, so as to leave an opening at the top for the pitman or pump-rod A to pass through and another long and narrow slot or opening, g , at the bottom.

The casing formed by the plates F F G G is inserted vertically between uprights $h h$ within the hopper, and is adjustable therein by means of pins or bolts i , which are inserted through perforations in the uprights h and perforated 80 ears k upon each end of the gate, so that it may be raised or lowered to regulate the rate of grinding, and allows the use of a large hopper full of grain without danger of choking up the mill or grinder. By withdrawing the bolt b 85 the pitman is ungeared from the grinding-plate B, and the grinder will stop operations without in any way disturbing or interfering with the working of the pumping apparatus.

Having thus described my invention, I 90 claim and desire to secure by Letters Patent of the United States—

1. In a feed-mill, a flat reciprocating grinding surface or blade, B, provided on both sides with an upper set of corrugations or serrations, 95 c' , pointing with their cutting-edges in a downward direction, and a lower set or series of corrugations or serrations, c , inclining downwardly from both edges toward the center at gradually-increasing pitch from top to bottom, substantially as and for the purpose herein shown and set forth.

2. In a feed-mill, a flat reciprocating grinding surface or blade, B, the inclined corrugations *c* of which are so arranged upon opposite sides or grinding-faces of the blade as to break joints or alternate with each other, the said corrugations or serrations upon each side inclining in a downward direction from both edges toward the center at gradually-increasing pitch from top to bottom, substantially as and for the purpose shown and specified.
3. In a vertical reciprocating feed-mill, the combination of the frame D, adjustable vertical casing-plates C C, vertical reciprocating grinding-blade B, having central socket or en-

largement, *a*, detachable pitman or pump-rod 15 A, hopper E, provided with the perforated uprights *h h*, and vertical adjustable feed-gate F F G G, having openings at the top and bottom, all constructed and combined to operate substantially in the manner and for the purpose herein shown and set forth.

In testimony that I claim the foregoing as my own I have hereunto affixed my signature in presence of two witnesses.

LOYD JOSEPH CALDWELL.
